UNITED STATES PATENT OFFICE.

FREDERICK L. FOX, OF WASHINGTON, DISTRICT OF COLUMBIA.

SPARK PLUG.

Application filed August 12, 1922. Serial No. 581,529.

This invention relates to improvements in spark plugs, the general object of the invention being to provide means for keeping the spark gap clear without removing the plug 5 from the engine.

Another object of the invention is to so form the plug that a portion of the wall of the shell acts as one member of the spark gap, with means for keeping the major portion 10 of this wall covered and uncovering new portions when the uncovered portion has become dirty.

A still further object of the invention is to provide means whereby the covering member for the wall can be adjusted from the exterior of the motor, by a wrench or the like, and without removing the plug from the 15 motor.

The invention also permits the cover member to be adjusted to expose a fresh sparking surface without stopping the motor so that it is not necessary to go to the trouble of stopping and starting the motor to find out whether or not the difficulty lies in the plug.

This invention also consists in certain other 20 features of construction and in the combination and arrangement of the several parts, to be hereinafter fully described, illustrated in the accompanying drawings and specifically 25 pointed out in the appended claims.

In describing my invention in detail, reference will be had to the accompanying drawings wherein like characters denote like or corresponding parts throughout the several 30 views, and in which:—

Figure 1 is an elevation of a plug constructed in accordance with this invention.

Figure 2 is a longitudinal sectional view with the interior parts in elevation.

Figure 3 is a longitudinal sectional view 40 through the entire plug.

Figure 4 is a section on line 4—4 of Figure 1.

Figure 5 is a longitudinal sectional view 45 showing a modification.

Figure 6 is a view of a further modification, parts being shown in section.

Figure 7 is a similar view of a further modification.

Figure 8 is a fragmentary sectional view 50 of still another modification.

In these views 1 indicates the shell, 2 the porcelain body, 3 the nut for holding the body in the shell and 4 the electrode which passes

through the porcelain body and is threaded 55 at its upper end to receive the usual nuts 5. As will be seen the ground electrode is formed by the inner wall of the lower part of the shell, the electrode 4 having its end bent, as at 6, so that the gap is formed by this bent end and a part of the wall of the shell. In carrying out my invention I provide a sleeve 7 for covering the major portion of the wall forming the ground electrode, said sleeve having an opening 7' therein for exposing a portion of this wall, adjacent the bent end 6 of the electrode 5, so as to form the spark gap. By turning this sleeve to expose new portions of the wall the spark gap can be kept clear and the foreign matter deposited on the portion previously exposed will be scraped off by the edges of the sleeve forming the walls 60 of the opening. The parts are so arranged that the sleeve can be turned without removing the plug from the engine and in order to keep the electrodes in their proper relative positions the insulated body with the electrode 4 must move with the sleeve. In the first form of the invention the sleeve carries the body 2 and is connected therewith by having a ring-shaped part 8 pressed into a groove 9 formed in the body. The outer end of the sleeve is provided with a wrench receiving head 10 and it is provided with an enlarged 65 central part 11 forming shoulders for engaging the gaskets 12 which act to make a gas tight joint between the sleeve, the shell and the nut. The lower end of the sleeve is bent over the end of the shell, as shown at 13, and the opening 7' extends through the inner 70 edge of this bent over part so that a gage or the like can be inserted into the opening to gage the spark gap. It will thus be seen that when the spark gap becomes filled or partly filled with foreign matter it is simply 75 necessary to place a wrench or the like on the head 10 and gives the sleeve a slight rotary movement so as to expose a new portion of the wall forming the ground electrode. As the porcelain body moves with the sleeve the 80 parts 6 of the electrode 4 will remain in the same position relative to the opening 7' at all times. As the sleeve is turned the edge wall of the opening 7' will act to scrape the 85 foreign matter from the wall of the shell so that the sleeve not only acts to keep the major portions of the wall covered but it also acts to remove carbon and the like from the parts 90

which have been exposed. As the bottom of the opening is not closed the matter scraped off by the walls thereof will drop from the plug and not accumulate therein which might 5 cause a short circuit.

In the modification shown in Figure 5 the enlargement 11' of the sleeve is made hollow so that this part of the sleeve can yield somewhat under the pressure of the nut and thus 10 facilitate the adjustment of the sleeve in the shell when a new part of the wall is to be exposed. This figure also shows the end of the sleeve as being unbent with the opening 7" extending entirely through the end of the 15 sleeve. In other respects this form of the invention is similar to the first form.

Figure 6 shows the invention applied to a plug, the parts of which cannot be separated.

In this form of the invention the parts are 20 held in the shell by a flange 13 on the shell being bent over upon a ring 14 which holds the sleeve and body in the shell. In other respects this form of the invention is similar to those described above.

25 In the form shown in Figure 7 the ring 14 is omitted and the sleeve 7* does not extend through the shell at its upper end but terminates just above the lower shoulder of the shell. The upper end of the sleeve is provided with tongues 15 which engage recesses 17 in the porcelain body so that the sleeve must turn with the body. The upper end of the porcelain body is provided with a metal cap 18 formed to receive a wrench, this cap 30 protecting the porcelain from injury by the wrench. Gaskets 19 are placed between the upper end of the sleeve and the shell and between the shell and the porcelain body so as to prevent leakage at these points. A gasket 35 19' is placed between the flange 13' of the shell and the upper shoulder of the body. Thus when the porcelain body is turned by a wrench or the like the sleeve will move with the body so as to expose a new portion 40 of the ground electrode.

45 In the form shown in Figure 8 the portion of the shell forming the ground electrode is beveled, as at 20, and the covering portion of the sleeve is also beveled, as at 21, so as 50 to engage the bevel 20. An opening 22 is formed in this beveled part 21. In this case the main electrode has its end of hook shape so as to bring the extremity within a sufficient distance of the ground electrode.

55 From the foregoing it will be seen that the spark gap can be kept clear by a slight movement of the sleeve, this movement being given the sleeve from the outer part of the plug, so that it is not necessary to remove the plug 60 from the engine or even stop the engine.

It is thought from the foregoing description that the advantages and novel features of my invention will be readily apparent.

65 I desire it to be understood that I may make changes in the construction and in the

combination and arrangement of the several parts, provided that such changes fall within the scope of the appended claims.

What I claim is:—

1. A spark plug having one of its spark gap members formed by a part of the wall of the shell, and an adjustable sleeve covering the wall, said sleeve having an opening therein for exposing a part of the wall. 70

2. A spark plug having one of its spark gap members formed with a broad surface, a sleeve covering the major part of this surface and leaving a portion uncovered and means for adjusting the sleeve to expose a new part of the surface, said means being operable 75 from the exterior of an internal combustion engine when said spark plug is applied thereto.

3. A spark plug of the class described comprising a shell having a part of its lower wall forming the ground electrode, an insulated body in the shell, an electrode carried thereby, and a covering member for the wall of the shell having an opening for exposing a portion of the wall adjacent the 85 main electrode and means for moving the said member with the insulated body to bring the opening over a new portion of the wall. 90

4. A spark plug of the class described comprising a shell having part of its wall forming 95 the ground electrode, a sleeve in the shell having an opening therein for exposing a part of the wall, an insulated body carried by the sleeve and movable therewith and a main electrode carried by the body. 100

5. A spark plug of the class described comprising a shell having part of its wall forming the ground electrode, a sleeve in the shell having an opening therein for exposing a part of the wall, an insulated body carried by 105 the sleeve and movable therewith, a main electrode carried by the body, said opening being so formed as to permit the introduction of a gage for measuring the spark gap.

6. In a spark plug, power and ground electrodes spaced apart to provide a spark gap, means fixedly associated with one of said electrodes and partially covering the second electrode and revoluble therein for presenting fresh sparking surfaces between the electrodes. 110

7. A spark plug comprising a shell, providing a ground electrode, a power electrode in the shell, means connected with and insulated from the power electrode adjustably secured in the shell for rotation and for frictional contact with the wall of the shell, said means having an opening arranged opposite the power electrode and the walls provided by said opening designed for scraping engagement with the shell when the power electrode and said means are turned in the shell to present fresh sparking gaps between the ground and power electrodes. 120

8. A spark plug having a shell electrode 130

- formed with a cylindrical bore, a bearing sleeve encasing a portion of the insulator carrying a center electrode, said bearing sleeve being mounted for rotatable adjustment in said shell electrode, said center electrode being formed for sparking cooperation with the cylindrical bore of the shell electrode, and said sleeve cooperating with the cylindrical bore for centering the shell and center electrode to maintain a uniform spark gap between said electrodes. 45
9. A spark plug having one electrode formed with a sparking surface, adjustable means covering a portion of such surface, a second electrode carried by said means for sparking cooperation with the first electrode, and means having a part for adjusting the first-mentioned means to uncover new portions of said surface of the first-mentioned 50 electrode for sparking cooperation with the second electrode. 55
10. A spark plug having a ground electrode formed by a portion of the wall of the shell, an adjustable covering member in frictional engagement with said wall, a second electrode carried by said covering member having sparking cooperation with the wall of said ground electrode, and means on said covering member operable to adjust said member for 55 uncovering new portions of the wall of the shell for sparking cooperation with said second electrode. 60
11. A spark plug having a shell electrode, an insulator mounting a central electrode, a bearing member mounting said insulator having an adjustable mounting in the shell electrode, and means on said member having a part for cleaning the shell electrode in the rotation of said member. 65
12. A spark plug comprising a pair of relatively rotatable electrodes, and means having a part mounting one of said electrodes and having a rotatable bearing in the other electrode and centering said electrodes, said 70 means serving to maintain uniform sparking cooperation of said electrodes. 75
13. A spark plug comprising a pair of relatively rotatable electrodes, one of said electrodes having a substantially cylindrical surface for sparking cooperation with the other electrode, and means mounting said other electrode and providing a bearing therefor in the first-mentioned electrode, said means having a part operable for cleaning the cylindrical sparking surface. 80
14. A spark plug comprising a pair of relatively rotatable electrodes, one of said electrodes having a point for sparking cooperation with a cylindrical surface formed in the other electrode, and means having a part mounting the first-mentioned electrode and providing a bearing therefor in the last-mentioned electrode, said means centering said electrodes to provide a substantially uniform spark gap in all positions of adjustment. 85
15. A spark plug comprising a pair of relatively rotatable electrodes, one of said electrodes having a point for sparking cooperation with a cylindrical surface formed in the other electrode, and means mounting the first-mentioned electrode, providing a bearing therefor in the last-mentioned electrode, said means centering said electrodes to provide a substantially uniform spark gap in all positions of adjustment, said means having a part 90 formed to clean the cylindrical sparking surface. 95
16. A spark plug comprising a pair of electrodes adapted for sparking cooperation, one of said electrodes having a cylindrical sparking surface, and means rotatable in one of said electrodes formed for contact with said cylindrical surface, said means having a part operable from the exterior of the spark plug when applied in operative position on an internal combustion engine. 100

In testimony whereof, I affix my signature.
